UNITED STATES PATENT OFFICE.

BERNIS M. SHIPLEY, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

CASH REGISTER.

Original application filed January 2, 1923, Serial No. 610,273. Divided and this application filed October 31, 1925. Serial No. 66,054.

This invention relates to cash registers and more particularly to the printing mechanism thereof. The invention is shown applied to a machine of the type shown and described in the patent to W. A. Chryst, No. 1,230,864, issued June 26, 1917; and in the patents to F. L. Fuller, Nos. 1,242,170 and 1,394,256, issued on October 9, 1917 and October 18, 1921, respectively; the patent to Shipley, No. 1,619,796, issued March 1, 1927, and the co-pending application of the present applicant Serial No. 610,273, filed January 2, 1923, of which this application is a division. Reference should be made to the above mentioned 15 patents and application for a complete understanding of the present invention.

An object of the present invention is to provide mechanism for automatically adjusting the printing elements appropriate to the 20 two transaction banks by means other than the regular adjusting mechanism, said adjustment being under the control of the total lever.

A specific object of this invention is the provision of means for setting up a designating character for a totalizer during total printing operations only.

With these and incidental objects in view, the invention consists of certain novel features of construction and combinations of parts, the essential elements of which are set forth in appended claims and a preferred form or embodiment of which is hereinafter described with reference to the drawings which accompany and form part of this specification.

Of said drawings:

Fig. 1 is a section through the machine taken just to the right of the withdrawal bank.

Fig. 2 is a side elevation of the total lever plate and the means connecting it with the printer.

Fig. 3 is a diagrammatic view of the two control banks and the total lever.

Fig. 4 is a detail side elevation of one of the type lines.

Fig. 5 is a detail side view of the deposit rack and a portion of the mechanism which cooperates therewith.

Fig. 6 is a detail side elevation of the rack operated by the total lever.

Fig. 7 is a plan view of the mechanism appearing in Fig. 5.

Fig. 8 is a view in perspective of a part of the mechanism for selecting the transaction rack to be moved to the left.

The machine of the application, of which this application is a division, has two groups or lines of totalizers known as the "Deposit" and "Withdrawal" totalizers. It also includes another line, viz, the upper totalizer line, on which is mounted an adding and subtracting totalizer to which no further reference need be made in this application. There is a separate totalizer on the first two lines appropriate to each key of the deposit and withdrawal banks. In addition, there is a totalizer on each of these lines which is selected for operation when there is no key depressed in the corresponding bank and the differential latch is disconnected in the "zero" position. As shown in Fig. 3, in which the well known totalizer line engaging controlling disks are disclosed, the upper disk controlled from the deposit bank is provided with high points 7 and 8 to cause the selected totalizer on the front or withdrawal line to engage the actuators when the B. Dep. and A. Dep. keys are depressed. The lower disk also has high points 7 and 8 to cause the selected totalizer on the back or deposit line to engage the actuators when this disk is adjusted into these positions under control of the B-WDR and A-WDR keys of the withdrawal bank. The totalizer in the "zero" position of the deposit bank, therefore, accumulates the total withdrawals or total debits, and the totalizer in the "zero" position of the withdrawal bank accumulates the total of all 75

deposits, or total credits.

There is a pair of type wheels appropriate to the withdrawal bank and another pair for the deposit bank. When no key in a bank is depressed, the type wheels for this bank will remain in the "zero" position. There is no type in this position. When it is desired to take a total from the Total debits totalizer, for instance, the total lever, the functions of which are well known, is moved to the position appropriate to the deposit bank, in the "zero" position of which this totalizer is located, but no key is depressed. The Total debits totalizer will, therefore, be selected 100

and engaged and the total thereon printed. The deposit type wheels will normally remain in their "zero" positions, but this invention includes mechanism which will move the deposit type wheel one space in order to bring type to the printing line which will print an identification, as "T Dr.". The same thing is true when the total lever is moved to the "Withdrawal" position. The mechanism will 10 then be operated to move the withdrawal rack and bring the type wheels from their zero positions to position to print an identification, as "T Cr.". The mechanism for accomplishing this result will now be described in 15 detail.

Withdrawal and deposit banks.

The withdrawal and deposit banks are substantially the same with the exception of 20 a few minor differences. These differences, however, do not in any way affect the present invention, and therefore, it is felt that the description of one of these banks and the differential mechanism therefor, will be sufficient for both.

In Fig. 1 the withdrawal bank is shown. It is provided with nine keys 30, mounted in a key frame 31, supported on the rods 32 and 33 in the usual manner. Each of the keys 30 30 has a shoulder 34, adapted to cooperate with a pin 35, carried by a detent bar 36, supported by pivoted links 37 and 38 pivoted to the key frame. When a key is depressed, the shoulder 34 passes beneath the pin 35 and is thereby held in its depressed position. The link 38, which supports the lower end of the detent bar 36, is extended to form a hook 39, adapted to cooperate with a pin 40, carried by a zero stop pawl 41, supported by a short 40 shaft 42, in the key frame.

When any key in the withdrawal bank is depressed, the zero stop pawl 41 for this bank is rocked to its ineffective position. If no key is depressed, the zero stop pawl is 45 adapted to disconnect the latch of the appropriate differential mechanism in a manner well known in the art, and described hereinafter.

The differential mechanism appropriate 50 to the withdrawal bank is a duplicate of that for the deposit bank, and therefore, the description of one will be sufficient for both.

The differential mechanism includes a differentially movable member 45, which carries a link 46 and a bell crank lever 47, pivoted thereto. This link and lever in turn pivotally support a latch 48, which cooperates with a shoulder formed on a driving segment 49, loosely mounted on a stud 50. The driving segment is rotated first clockwise and then counter-clockwise during each operation of the machine. This movement is given to the driving segment by means of a pair of cams 50, which together actuate a Y shaped 60 lever 51, well known in machines of this type.

This lever is connected by a link 52, to the driving segment 49.

During the clockwise movement of the driving segment, the forward end of the bell crank lever 47 contacts with whichever one of the keys in its appropriate bank has been depressed, and thereupon causes the latch 48 to be disconnected from the shoulder of the driving segment 49, which continues its clockwise movement. If no key in a bank is depressed, the latch is disconnected by the contact of the outer end of an arm 53 with the zero stop pawl 41. The arm 53 is journaled at its inner end on the stud 50 and at its outer end, is connected to the forward end of the bell crank lever 47 by a slot-and-pin connection, as is well known.

Pivoted to the differentially movable member 45 is a beam 55. This beam 55 is bifurcated at its right-hand end, and cooperates with a pin 56 carried by a link 57. At its upper end, the link 57 is connected to a segment 58, the purpose of which is well known and will not be described herein. At its lower end, the link 57 is pivoted to an arm 59, secured to a spiral segment 60, loose on a rod 61, supported by the machine side frame. Segment 60 meshes with a spiral gear 62, fast on the shaft 63, which is supported by the printer frames 64 and 65. At its forward end, the shaft 63 carries a segment 66, (Figs. 1 and 5), which meshes with teeth formed on the lower edge of a rack 67 extending across the machine. Rack 67 is slidably mounted on three studs 68, which are supported by the printer frame.

Printing mechanism.

On its upper edge, the rack 67 carries teeth 69, adapted to mesh with a pinion 70, supported on a shaft. This pinion is connected by a tube to another pinion 71 (Figs. 5 and 7) which meshes with two type wheels 72 and 73, loose on rods 74 and 75. It can be seen that the differential movement of the differentially movable member 45 is transmitted through the beam 55, link 57, spiral gear 60, spiral gear 62, shaft 63, segment 66, to the rack 67, which, in turn, operates the pinions 70 and 71, and causes both of the type wheels 72 and 73 to rotate to a position corresponding with the key depressed in the appropriate bank. It will be understood that there is one of these racks 67 appropriate to each of the withdrawal and the deposit banks.

Fig. 4 shows one of the type lines which carries the type wheels 72 and 73. This figure is a top plan view of the upper type wheels 72. There are four groups of amount type wheels 78, two type wheels 72 appropriate to the withdrawal and deposit banks, and six type wheels 79 appropriate to the ledger number keys, which are not shown and described in this application.

It will be noted that the type wheels 72, 130

which are shown in their normal positions, do not carry type at the printing line. In the position below the blank position, however, it can be seen that the types "TD" and "TC" appear, these letters standing for Total debit and Total credit.

It can be seen from Fig. 3 that should the total lever 123 (Fig. 2) be moved downward in the slot 80 to the second position below its adding position, which position is appropriate to the deposit bank, and should no key in the deposit bank be depressed when the machine is operated to take a total, the totalizer which is appropriate to the "zero" position of the deposit bank will be selected. This totalizer is for the purpose of accumulating the total withdrawals or debits. When this operation occurs, it is desired to print "TD" for Total debit on the record receiving medium, but as the "zero" position of the rack 67 is a blank position, it is necessary on this operation to move the rack one position to the left. This movement of the rack 67 to the left will set up the total debit type at the printing line, in order that this designation may be printed with the total from the Total debit totalizer.

The mechanism for accomplishing this one-step movement of the rack 67 on this operation, will now be described:

The invention utilizes mechanism which has been known in machines of this type as the zero elimination mechanism, in order to accomplish the function above pointed out. It will be recalled that the zero elimination mechanism is for the purpose of moving the racks associated with amount type wheels of higher denominations than that on which appears the highest significant digit of the amount being set up on the type wheels in order to remove the zeros of the amount type wheels, which zeros are normally in the zero position, so as to bring a blank position of the type wheels to the printing line. Each of the racks 67 (Fig. 5) appropriate to the withdrawal and the deposit banks, has a projection 90 on its left-hand end, adapted to cooperate with a shoulder 91, formed on a coupling member 92, pivoted to one arm of a bell crank lever 94, loose on a shaft 95, supported by the printer frame.

A link 95 connects the remaining arm of the bell crank lever 94, with a bell crank lever 96, loose on a rod 97. The bell crank lever 96 carries two rollers 98 and 99 which cooperate with a pair of cams 100 and 101, fastened on a shaft 102, which is the main drive shaft of the printing mechanism. This shaft receives one rotation in a counter-clockwise direction at every operation of the machine. The formation of the cams 100 and 101 is such that the bell crank lever 96 will be rocked first clockwise from and then counter-clockwise to its normal position.

The clockwise movement of the bell crank

lever 96, will, through the link 95, rock the bell crank lever 94 clockwise and then counter-clockwise.

The rack 67 is normally held against movement toward the left, due to a spring-pulled lever 104, loose on a shaft 105 and having a nose cooperating with a downwardly extending projection 106 on the rack. It is apparent from Fig. 5 that if the coupling member 92 is in the position shown in this figure, the clockwise movement of the bell crank lever 94 will have no effect on the rack. When printing a total of all deposit items, or of all withdrawals, it is desired to move the rack to the left in order to bring the appropriate designating type to the printing line, to which end, means is provided for lowering the coupling member 92 until the shoulder 91 thereon cooperates with the projection 90 on the rack. The coupling member 92 is normally held in its elevated position by means of an arm 108, loose on a rod 109, and having a projection 110 extending from its lower edge and resting on an appropriate cam disc 111.

Disks 111 fast with each other, turn on a suitable support and are positioned by the total lever 123 in a manner which will be hereinafter described. There is one of these disks appropriate to the deposit bank, and another appropriate to the withdrawal bank. The disk 111, shown in full lines in Figs. 5 and 6, is the one for the withdrawal bank, and partially hides the disk associated with the deposit bank. These disks are formed with high and low portions on their upper edges. The disk for the withdrawal bank is so formed that the arm 108 which rests thereon, will not be lowered until the total lever 123 is moved to one of its extreme upper or lower positions. The disk appropriate to the deposit bank, however, is cut away so that the arm 108 appropriate thereto will be lowered when the total lever is moved to either the second position above or the second position below its adding position. Should the total lever be moved to its first position above or below its adding position, the disks both have high portions in these positions, thereby preventing either of the arms 108 from being lowered. When the disks 111 are moved to the position in which the arm 108 for the deposit bank will be lowered, it is evident that the rack 67 for the deposit bank will be moved one step toward the left, and likewise it can be seen that when the disk 111 for the withdrawal bank is positioned so that the arm 108 appropriate thereto is lowered, the withdrawal rack will be moved one step, in order to bring the Total credit and Total debit designations to the printing line.

The means whereby the disks 111 are adjusted by the total lever 123, will now be described.

The disks 111 have fast thereto a segmental

member 113, which meshes with teeth 114 of a rack 115 (Fig. 6) slidably mounted on the two right-hand studs 68, above mentioned. At its right-hand end, this rack carries teeth 116 which mesh with teeth formed on a segment 117, fast on a shaft 118. The shaft 118 at its inner end carries a spiral gear 119 (Fig. 2), which meshes with the spiral segment 120, to which is secured an arm 121, loose on the rod 61. A link 122 pivotally connects the arm 121 with the total lever plate 123, which plate is old and well-known in machines of this type. It can be seen that when the total lever is moved down, the plate 123 will be rotated in a counter-clockwise direction. This will raise the link 122 and rock the arm 121 and spiral segment 120 counter-clockwise, thereby rotating the spiral gear 119, shaft 118 and segment 117 (Fig. 6) in a counter-clockwise direction. This will move the rack 115 toward the left, and through the segment 113, will drive both of the discs 111 in a clockwise direction a sufficient distance to position the discs appropriately to the position of the total lever.

Operation.

If a deposit is to be entered, one of the deposit keys 30 (Fig. 1) is depressed which causes a corresponding totalizer (not shown) to be selected and engaged with the actuators, and appropriate type characters to be set up. At the same time a totalizer corresponding to the "zero" position of the withdrawal bank 35 and selected under control of the zero stop pawl in such bank, is also engaged with the actuators. The amounts of the deposits are added individually into the totalizer selected under the control of the zero stop pawl of the withdrawal bank, as well as into the totalizer selected under control of the key depressed in the deposit bank. As the type wheels associated with these banks of keys have blank zero positions, no characters will be printed 40 corresponding to the totalizer selected under control of the zero stop pawl of the withdrawal bank. When the total lever 123 is moved out of its adding position into a position corresponding to the withdrawal bank 45 and the machine is operated without depressing a key in said bank, the totalizer corresponding to the "zero" position of the withdrawal bank is selected and engaged and the rack setting mechanism in Fig. 5 is permitted 50 to function to move the rack 67 one step to the left to set up a character indicating that the figures printed represent the total in the deposit totalizer.

Thus in entering a series of deposits and 55 withdrawals, the operator will set up the amount of each item, press the proper transaction key 30 in the deposit or withdrawal bank (Fig. 3) and operate the machine.

The key 30 will select the proper transaction totalizer on the front or back totalizer

depending upon the key selected, but since only a single key 30 is depressed, the zero stop pawl 41 in that row wherein no key is depressed, controls the position of the corresponding differential arm 45, the latch of 70 which is disconnected in the zero position to automatically select the grand totalizer for that column wherein a key has been depressed. Thus the zero stop pawl associated with the withdrawal bank of keys 30 selects 75 for operation the grand totalizer on which all deposit items are registered, and vice versa.

There is a rack bar 67 (Fig. 5) for each row of transaction keys 30, and depending upon the particular key 30 depressed, the corresponding rack will be adjusted through the differential arm 45 (Fig. 1), beam 55, link 57, arm 59, worm segment 60, gear 62, shaft 63, and toothed segment 66 (Fig. 5) to cause the rack teeth 69 to turn the appropriate wheel 71 meshing with the pair of type carriers 72, 73 to set the proper type at the printing line.

So long as the total lever 123 remains in the "add" position, the racks 67 can reciprocate to any extent permitted by the particular key 30 depressed, the projections 90 on the racks passing freely beneath the shouldered coupling members 92 which are supported in their elevated idle positions by the arms 108, and although the coupling members travel back and forth at each operation of the machine, the supporting faces of the arms 108 are of sufficient extent to maintain the coupling members idle, so long as the high spots or lobes of the cam disks 111 remain in the 100 path of the projections 110 on the arms 108.

In the particular embodiment of the invention herein selected for illustration, the various classes of deposit items are registered on their corresponding totalizers arranged 105 on the back totalizer line, and the various classes of deposit items are registered on their corresponding totalizers on the front totalizer line, but the totalizer on which is accumulated the grand total of all the deposit items, is arranged on the front totalizer line, in alignment with the withdrawal item totalizers, and vice versa. Adjustment of the total lever 123 from its normal "add" position to any of its other positions, operates 110 mechanism to select one or another of the totalizer lines as desired.

When it is desired to take a total of the deposits, for instance, the operator shifts the total lever 123 from its normal "add" position, to a position to select the front totalizer line for operation, and as the "deposit" grand totalizer is at one end of the front totalizer line, it is selected by the zero stop pawl 41 for the withdrawal bank.

Adjustment of the total lever 123 to its lowest position to select the front totalizer line, operates through link 122 (Fig. 2), arm 121, worm segment 120, gear 119, shaft 118, sector 117, and rack 116 (Fig. 6) to shift 125

the bar 115 carrying the rack and with it the rack 115 in mesh with the mutilated gear 113 fast with the cam disks 111.

The mutilated gear 113, when rotated, turns 5 the disks 111 from their normal positions wherein the lobes on both cam disks support the arms 108 in their elevated positions, and hence maintain the coupling members 92 in idle position. Assuming that the total lever 10 123 has been shifted to its extreme lowest position (Fig. 3) the disks 111 will have been turned so that the single broad lobe of the foremost disk, seen in Fig. 5, will pass from beneath the projection 110 on the foremost 15 arm 108, whereupon the foremost spring-actuated coupling member 92 will rock in clockwise direction until its shoulder 91 rests on the bar 67 just in front of the projection 90 on such bar.

20 At the same time the rearmost cam disk 111 which has three successive lobes formed on its periphery, turns to free its supporting arm 108, whereupon the corresponding coupling member 92 rocks clockwise, but is immediately restored to idle position by the succeeding shorter lobe, so that when the total lever 123 is in its extreme lowest position of adjustment, the rearmost cam disk 111 maintains its arm 108 in elevated position to 25 hold idle its coupling member 92 (concealed behind the coupling member 92 seen in Fig. 5).

The machine, when operated under this adjustment, rotates the shaft 102 and its cams 30 100, 101 to rock the bell cranks 96, 94. Bell crank 94 rocks clockwise and then counter-clockwise. On its clockwise operation it draws the coupling members 92 to the left, the foremost coupling member 92 drawing with 35 it the foremost bar 67 one step past its normal "zero" position, against the tension of the spring-actuated restoring dog 104, the supporting rods 68 and the slots in the bar 67 permitting this one step backward movement 40 of the bar. And the bar 67, through its rack 69, pinion 70 (Figs. 5 and 7), sleeve, and pinion 71, rotates the corresponding upper and lower type wheels 72, 73 one step backwardly 45 past their normal blank positions to locate 50 the proper designating type "TD" at the printing line.

The rearmost coupling member 92 (not seen) operates similarly but being held in idle position by its arm 108 performs no function.

55 As the machine completes its operation, cam 100 on shaft 102 wipes against roll 98 to restore the bell cranks 96, 94 to their home positions, at which time the coupling members 92 lie in their extreme forward or right-hand positions, viewing Fig. 5, the foremost coupling member, however, resting on the bar 67 until the total lever 123 is shifted to its intermediate or "add" position, preparatory

to accumulating another set of deposits and 65 withdrawals.

The effective coupling member 92 when restored to its right-hand position, enables the spring-actuated dog 104 to restore the particular bar 67 actuated one step to the 70 right, to position type wheels 72, 73 with their blank spaces at the printing line.

In the foregoing description, it has been assumed that the bar 67 lies in its home position at the time when the total lever is shifted 75 to its extreme lowest position.

Due to the usual minimum movement mechanism with which machines of this type are equipped, the bars 67 will most probably occupy any of their other positions, rather than 80 their home positions.

"Read" and "reset" operations on these machines involve a double operation, as is well known in the art, during the first half of 85 which, the bars 67 are restored to their home positions.

Consequently when the selected coupling member 92 is released by its arm 108 and rocks clockwise towards the bar 67 the elongated finger projecting to the right (in Fig. 5) from the shoulder 91 on the coupling member rests upon the projection 90 in whatever position it may be, other than its home position, to prevent the shoulder 91 from dropping behind the projection 90, and as soon as the bar 67 is restored to its home position in a total taking operation, the projection 90 escapes the finger, and the coupling member 92 snaps its shoulder 91 in front of the projection 90.

The operation with respect to withdrawals and the totals thereof is the same as for deposits.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within 105 the scope of the claims which follow.

What is claimed is:—

1. In a cash register, the combination of a plurality of racks for setting type wheels, a plurality of banks of keys for controlling 115 the movement of said racks in one direction, means for moving said racks in the opposite direction, and a manually movable lever, the movement of which selects which of said racks is to be moved in said second mentioned direction.

2. In a cash register, the combination of a plurality of racks for setting type wheels, differential mechanism for moving said racks in one direction, a plurality of hook members 125 for moving said racks in the opposite direction, means for preventing certain of said racks from being moved in said second men-

tioned direction, and a manually operable lever for controlling said last mentioned means.

3. In a cash register, the combination of a plurality of type wheels having a blank space normally on the printing line, means for rotating said type wheels to a variable extent in one direction, and manually selected means for rotating said wheels one space in the opposite direction to bring a particular type to the printing line.

4. In a cash register, the combination of a plurality of type wheels having a blank space normally on the printing line, a plurality of racks adapted to be moved in one direction to set the said wheels differentially, a plurality of hook members adapted to move said racks in the opposite direction; and a single manipulative means to determine which of said hook members is to be effective.

5. In a cash register, the combination of a plurality of type wheels having a blank space normally on the printing line, a plurality of racks adapted to be moved in one direction to set the said wheels differentially, a plurality of normally disengaged hook members adapted to move said racks in the opposite direction, and a single manipulative means for selecting which of said hook members will be engaged.

6. In a cash register, the combination of a plurality of type wheels having a blank space normally on the printing line, a plurality of racks adapted to be moved in one direction to set the said wheels differentially, a plurality of hook members adapted to move said racks in the opposite direction, a plurality of arms for normally holding said hook members out of engagement with said racks, and a single manipulative means for controlling which of said arms will be operated to engage its hook member with its appropriate rack.

7. In a cash register, the combination of a plurality of type wheels having a blank space normally on the printing line, a plurality of racks adapted to be moved in one direction to set the said wheels differentially, a plurality of hook members adapted to move said racks in the opposite direction, a plurality of arms for normally holding said hook members out of engagement with said racks, a plurality of cam disks for supporting said arms, and a manually movable lever for positioning said disks so that one of said arms

and its hook member can be lowered into engagement with its said rack.

8. In a cash register comprising a bank of keys, a zero stop pawl, differential mechanism, and total controlling means, the combination of a type wheel bearing characters corresponding to the key-controlled positions of said differential, and provided with a blank space corresponding to the zero stop pawl-controlled position of said differential, and also bearing a character below said blank space, and means under control of said total controlling means for causing said last mentioned character to be positioned at the printing line when the differential is stopped by the zero pawl in total printing operations of the machine.

9. In a cash register comprising a bank of keys, a zero stop pawl, a differential mechanism, and a total controlling lever, the combination of a type wheel having characters in positions corresponding to said keys and in a position below the position corresponding to said zero stop pawl, means for adjusting said wheel under control of said keys for presenting appropriate characters at the printing line, a total control lever, and means under control of said lever for causing said character located below zero to be presented at the printing line when the machine is conditioned to print a total.

10. In a cash register comprising a bank of keys, a zero stop pawl, and a differential controlled by said keys and zero stop pawl, the combination of a type wheel adjustable under control of said differential, an adjustable total control lever, and means under control of said lever for adjusting said type wheel to an invariable position when the differential is controlled by the zero stop pawl in the total printing operations.

11. In a cash register comprising two banks of keys, zero stop pawls, differentials controlled by said keys and zero stop pawls, type elements adjustable by said differentials under control of said keys and zero stop pawls, means for controlling the machine to print totals, and means for positioning said type wheels to print characters designating the totals when the differentials are controlled by the zero stop pawls in total printing operations.

In testimony whereof I affix my signature.

BERNIS M. SHIPLEY.
